UNITED STATES PATENT OFFICE.

ALEXANDER ROITZHEIM, OF DUISBURG, GERMANY.

PROCESS AND APPARATUS FOR REMOVING DROSSY RESIDUES FROM VERTICAL MUFFLES IN THE EXTRACTION OF ZINC.

1,144,066.

Specification of Letters Patent. Patented June 22, 1915.

Application filed September 22, 1913. Serial No. 791,108.

To all whom it may concern:

Be it known that I, ALEXANDER ROITZHEIM, a subject of the King of Prussia, German Emperor, and residing at the city of Duisburg, in the Kingdom of Prussia, German Empire, have invented certain new and useful Improvements in Processes and Apparatus for Removing Drossy Residues from Vertical Muffles in the Extraction of Zinc, 5 of which the following is a specification.

The smelting of zinc ores in vertical muffles for the purpose of zinc extraction presents no difficulties when the ores are not drossy, and has the advantage that the work 10 of cleaning out is very greatly facilitated. Ores of this kind are however very rare and the majority of the ores employed in practice are more or less drossy. The extent to which slagging occurs is manifested, 15 according to the kind of ore, in all stages between only slight sintering and complete softening of the residues of ore. The slags do not become actually liquid as this is prevented by the excess of reducing carbon 20 in the charge, just as the admixture of chamotte with rich clay make it "poor". But when vertical muffles are employed for smelting such ores, just this sintered or soft slag, which is still far from the condition 25 of a thin liquid, introduces the difficulty that the charge does not automatically slide down through the muffle, but mostly remains adherent to the walls of the muffle. Therefore when smelting drossy ores in vertical 30 muffles the same cleaning work is necessary as in horizontal muffles, wherefore the employment of vertical muffles has practically no advantages at all as compared with that of horizontal muffles. In addition, 35 when the ores slag very considerably, the devices in the muffles for drawing off the zinc vapors and reduction gases, which devices, owing to the considerable resistance offered by the high column of charge to the 40 passage of vapors, are undoubtedly necessary in vertical muffles, are soon choked up with incrustations of slag, and the continual replacement of these devices involves unnecessary expense.

50 The present invention relates to obviating these difficulties.

It substantially consists in a piston being pressed from above downwardly through the muffle, the sintered or scorified contents

of the muffle being thus driven out. The 55 piston moves of course with a certain play through the muffle so that it does not scrape the muffle walls, but when advancing takes with it the slags which adhere to the walls of the muffle. Since this piston is exposed 60 to heat and must have mechanical rigidity, it preferably consists of a refractory compound, as chromite; it suffices, however, to employ an ordinary refractory mass which frits together at the high temperatures pre- 65 vailing and consequently obtains rigidity in its heated condition. Owing to the comparatively long muffles used for smelting zinc, and also in the event of working having to be continuous a single piston scarcely 70 suffices for each muffle, but preferably several pistons are inserted into one muffle, as represented in the drawings.

Some preferred forms of apparatus for carrying my process into practice are repre- 75 sented by way of example in the accompanying drawings, wherein:—

Figure 1 is a longitudinal section through one muffle; Fig. 2 is a longitudinal section taken at right angles to the section plane of 80 Fig. 1, and Fig. 3 is a cross section through the muffle. Figs. 4-8 illustrate the type of muffle and pistons for ores that slag considerably: Fig. 4 being a longitudinal section of such a muffle; Fig. 5 a longitudinal 85 section taken at right angles to Fig. 4; Fig. 6 a cross-section of the muffle taken through the fume ducts on line A—B Fig. 4; Fig. 7 a top plan view of the muffle, and Fig. 8 a cross section of the muffle taken below the 90 fume ducts on line C—D Fig. 4.

Referring to the drawing, *a* is a vertical muffle; it is located in a heating chamber having the known construction of the gas or half-gas furnace. 95

b are gas discharge ducts through which pass the reduction gases and zinc vapors, in order that they may collect in the receivers *c*. These ducts start at a certain distance below the upper opening of the muffle and 100 finish at a certain distance from the lower opening, so that the charge or the residues reliably shut off the outside air. In the drawing, these ducts are shown as perforated walls; instead of this device, another 105 of the known devices of this kind can however be employed, but, in any case, the withdrawal of the vapor is intended to begin at

d and to finish at *e*, in order that the vapors may be prevented from coming into contact with the outside air.

f are pistons which pass with the necessary play through the muffle.

The mode of working is as follows:—The muffle is filled, as shown, with the charge and the pistons. When the charge is reduced by the action of the high temperature 10 in the furnace chamber, the door of the bend *g* or of a similar device is opened, and the charge therein consisting of reduced residues is withdrawn. Simultaneously mechanical pressure is applied from above to 15 the top piston and the latter is therefore pressed downwardly a certain distance. This distance corresponds to the length of the projection or separate stem *h* on the piston, and the arrangement is such that a fresh 20 piston, which is set in place after the pressure member has been raised, stands somewhat above the upper edge of the muffle in such manner that the charge can be filled in at *i*. This cycle of operations is thereupon 25 repeated until the muffle is again filled with a piston and a charge. In the bend *g* there obviously remains behind both a part of the residues from the previous reduction and pistons, so that the fresh charge is only 30 in the muffle.

The mode of working is described above for the case in which the muffle is intended to be entirely emptied and filled in one cycle of operations. Smelting can however be 35 carried out continuously, in which case only a single piston and a correspondingly small quantity of residues are discharged at the outlet for the residues, and at certain intervals of time depending on the rapidity of 40 the reduction process a new piston and a new charge is pressed in. The zinc vapors can escape neither upwardly nor downwardly, as the second piston is never pressed down from above to a point below the top 45 gas-ducts, but remains somewhat above the latter, while the charge in the bend *g* prevents the vapors escaping below.

The above described apparatus is preferably employed for ores which indeed sinter, 50 but do not slag so considerably that the gas-ducts become wholly filled up. The pistons therefore have only to bring about a uniform passage of the charge through the muffle. For ores which slag considerably and gradually block up the gas-ducts, the individual pistons have a special form, represented in 55 the retort illustrated in Figs. 4 to 8. In Figs. 4 to 8 the retort is shown as provided with two fume channels *m* that have open 60 slots in the walls adjacent the charge, and the pistons are H-shaped to slide along the

channels. The stems of the pistons have horizontal, transverse passages *l* that register with the slots in the fume channels. Passages *k* partly in the pistons proper and 65 partly in their removable stems connect with the passages *l* so that the fumes and gases below the piston rise through the passages *k* into those *l* and are thereby discharged into the open slotted side of channels *m*. The 70 mode of working remains the same as that hereinbefore described, but each individual piston has gas-ducts through which the zinc vapors and reduction gases can pass. In those faces of the piston which face downwardly holes *k* are arranged connected to the duct *l* which in turn opens into the slots *m*, to and outside of which are directly connected the receivers. The zinc vapors and reduction gases from the charge which 75 is held by each individual piston escape through the holes *k* and the duct *l* into the slots *m* and then pass to the receivers. Since the slag tends to sink, the holes *k* remain open; moreover, after each passage of the 80 pistons through the muffle there is an opportunity of checking whether the holes are blocked up or not. The slots *m* are protected from the entry of the charge by the stems of the pistons. 90

I claim—

1. A zinc retort piston of refractory material substantially filling the retort, having a refractory stem for supporting the piston thereabove to maintain adjacent pistons 95 spaced and provide a chamber for the charge without compressing the same.

2. A zinc retort piston of refractory material having a refractory stem removable from, arranged to rest on and interfit with 100 the piston.

3. A retort piston of refractory material having a refractory stem and ducts for fumes and gas for connecting the space on one side of a piston to that on the other. 105

4. A retort piston of refractory material having a separate stem of refractory material interfitting with the piston, and ducts, partly in the piston and partly in the stem, and arranged to conduct fumes and gas from 110 one side of the piston to the other.

5. The method of working zinc retorts which comprises passing through an open-ended retort a plurality of separately supported quantities of the charge. 115

In testimony whereof I have affixed my signature in presence of two witnesses.
